(57) **CLAIM**

What is claimed is an ornamental design for a breathing apparatus, as shown and described.

DESCRIPTION

FIG. 1 is a perspective view of a breathing apparatus showing my new design;

FIG. 2 is a front view thereof;

FIG. 3 is a rear view thereof;

FIG. 4 is a right side elevational view thereof;

FIG. 5 is a left side elevational view thereof;

FIG. 6 is a top plan view thereof; and,

FIG. 7 is a bottom plan view thereof.

The broken lines depict portions of the breathing apparatus that form no part of the claimed design.
